DESIGN FOR A FLASH LAMP HOLDER

John W. Barnes, Ann Arbor, Mich., assignor to
Argus, Incorporated, Ann Arbor, Mich., a cor-
poration of Michigan

Application November 25, 1946, Serial No. 135,057

Term of patent 14 years

(Cl. D48—24)

To all whom it may concern:

Be it known that I, John W. Barnes, a citizen of the United States, residing at Ann Arbor, in the county of Washtenaw and State of Michigan, have invented a new, original, and ornamental Design for Flash Lamp Holder, of which the following is a specification, reference being had to the accompanying drawing, forming a part thereof.

Figure 1 is a front elevation of an ornamental flash lamp holder, showing my new design;

Figure 2 is a side elevation of the flash lamp holder as viewed from the left of Figure 1;

Figure 3 is a top plan view of the flash lamp holder of Figures 1 and 2;

Figure 4 is a rear elevation of the flash lamp holder of Figures 1 through 3;

Figure 5 is a bottom plan view of the flash lamp holder of Figures 1 through 4.

The dotted line disclosure of the reflector in Figure 2 of the drawing is for illustrative purposes only.

I claim:

The ornamental design for a flash lamp holder, as shown and described.

JOHN W. BARNES.
